United States Patent Office.

WALDO E. HASKINS, OF NEW YORK, N. Y.

Letters Patent No. 67,111, dated July 23, 1867.

ENVELOPE.

The Schedule referred to in these Letters Patent and making part of the same.

TO ALL WHOM IT MAY CONCERN:

Be it known that I, WALDO E. HASKINS, of the city, county, and State of New York, have invented a new and useful improvement in Envelopes; and I do hereby declare that the following is a full, clear, and exact description thereof, which will enable others skilled in the art to make and use the same, reference being had to the accompanying drawings, forming part of this specification, in which—

Figure 1 represents the plan of the pattern in which the paper is cut for making a box-envelope.

Figure 2 is the front side view of a box-envelope with the lap partly open showing my improved double-folded corners.

Figure 3 is a partial perspective view of the same improvement in another aspect.

Similar letters of reference indicate like parts.

This invention relates to an improvement in the construction of box-envelopes for the purpose of closing the corners under the flaps and rendering them more serviceable for preserving documents and papers of all kinds, both as files and for remittance in the mails.

As box-envelopes are generally constructed the corners under the flaps are apt to flare open and expose the contents so that they may be easily abstracted or lost, or the dust, when filed, may enter and soil the papers. This improvement obviates these difficulties and makes the envelope more serviceable by strengthening the hinge or fold of the flaps where the wear and liability to injury are greatest. It consists in forming inward projections which connect the flap with the upper corners or ends of the box-envelopes, connecting the body and the flap of the envelope in such manner that when the flap is folded down the projections fold down inwardly and close the corners of the box perfectly, by which means the papers enclosed cannot be got at from the outside, nor can dust enter the envelope.

In fig. 1, which represents the pattern of a box-envelope as the paper is cut and creased before folding and pasting together to form it, A is the flap, B is the back, and C the top part. The other parts and divisions for folding and creasing are well understood and require no special explanation. My improvement is in the projections D D formed at the upper corners between the flap A and the end pieces E E, which form the ends of the box. These corner pieces are made in the cutting of the pattern of the envelope by leaving the material whole within the exterior lines a b c, connecting the flap A and the end pieces E E, and creasing the corners thus formed in the usual way for folding on the lines a d, b d, and d c. It will be observed that the corners D D are thus made as wide on the lines a d and d c as the end pieces E E, or as that part of the flap formed by doubling over in the creases a a and d d, so that when the flap A is shut the ends of the flap and the ends of the box itself are thus folded over inwardly together, forming a close corner, as shown in figs. 2 and 3. The projections D D may be made square or of trapezoidal form.

Having thus described my invention, I claim as new, and desire to secure by Letters Patent—

The trapezoidal projections D D of the box-envelope, between the flap A, ends E E, and the upper corners of the point B, folded in the medium line b d, and lines a d and d c, whereby the corners of the envelope are completely closed, substantially as described for the purpose specified.

The above specification of my invention signed by me this   day of October, 1866.

WALDO E. HASKINS.
